POWER-OPERATED SCISSORS

Vincenzo Gaudio, Cranston, R. I.

Application September 27, 1943, Serial No. 503,981

6 Claims. (Cl. 30—228)

This invention relates to power operated scissors and it is an object of the invention to provide an implement of this kind including relatively movable blades, together with means operable at the will of the user to cause such relative movement of the blades to be at one speed selected from several different speeds.

It is also an object of the invention to provide an implement of this kind including a motor carried by the implement for effecting, as desired, swinging movement of one cutting blade with respect to another and wherein means are provided to cause the movement of the swinging blade to be at such differing speeds within certain limitations as may be desired by the user.

The invention consists in the details of construction and in the combination and arrangement of the several parts of my improved power operated scissors whereby certain important advantages are attained, as will be hereinafter more fully set forth.

In order that my invention may be better understood, I will now proceed to describe the same with reference to the accompanying drawings, wherein:

Figure 1 is a view in top plan of power operated scissors constructed in accordance with an embodiment of my invention.

Figure 2 is a longitudinal sectional view taken substantially on the line 2—2 of Figure 1;

Figure 3 is an enlarged transverse sectional view taken substantially on the line 3—3 of Figure 2;

Figure 4 is an enlarged sectional view taken substantially on the line 4—4 of Figure 2;

Figure 5 is a detailed sectional view taken substantially on the line 5—5 of Figure 2; and

Figure 6 is a detailed sectional view taken substantially on the line 6—6 of Figure 2.

In the embodiment of the invention as illustrated in the accompanying drawings, M denotes an elongated tubular handle member of desired dimensions but of a size to be readily and conveniently held by a hand of the user. The outer end of the member M, which is tubular, is closed by a head or plate 1, which may be applied and held in place in any manner preferred.

The opposite end of the member M carries a hollow head H, herein disclosed as of a general pear-like form with the smaller end forwardly disposed and the rear larger end portion of a maximum diameter in excess of the adjacent inner end of the handle member H. It is believed to be obvious, however, that the form of

this head H may be of such other design or appearance as may be deemed preferable.

Mounted within the handle member M at the central portion thereof is an electric motor E of a type wherein the armature or drive shaft 2 has longitudinal movement so that the same may be shifted, as desired, to different selective positions for a purpose to be hereinafter explained.

This shaft 2, at required points fore and aft 10 of the motor E, carries the surrounding collars or flanges 2' which, by contact with the motor E, limit the endwise movement of the shaft 2 in either direction. The shaft 2 is of a length to have its forward portion at all times extending 15 within the head H, and the extremity of such forward portion, in the present embodiment of the invention, is formed to provide three successive steps 4, with the smallest of such steps outermost.

20 Slidably engaged on each of the steps 4 is a disk 5 having its periphery formed to provide a spiral cam, the high point of which in radial alignment with its low point at the edge portion b between such high and low points being 25 straight. The disk 5 is held in place upon its step 4 by a key 6, herein disclosed as a cotter pin, insertible through the shaft 2 in advance of and immediately adjacent to the applied disk.

The several disks 5 mounted on the steps 4 30 are of the same design but the high points thereof progressively differ with the disk having the shorter of such high points arranged innermost.

The outer end of the head H is formed to 35 provide a slot 7 through which extends the inner extremity of the stationary scissors blade 8, and such extremity within the head H is provided with a laterally disposed tang or short arm 9 to facilitate the rigid attachment of the 40 blade 8 by the bolts 10, or otherwise as may be desired.

Associated with the blade 8 and coacting therewith in a well known manner is the swinging scissors blade 11 having its inner or rear portion 45 pivotally held to the inner or rear portion of the blade 8 by a conventional pivot member 12. As shown in the accompanying drawings, this member 12 is placed exteriorly of the head H but in close proximity thereto.

50 The inner or pivoted end of the blade 11 is provided with an elongated and laterally inclined arm 14 which extends within the head H, through the slot 7 and with which is intended to selectively engage one of the disks 5, as determined by 55 the endwise adjustment or movement of the shaft

2. This arm 14 is constantly maintained in contact with the periphery of a disk 5 by the expansible or pressure member 15, herein disclosed as a coil spring, interposed between the arm 14 and the wall of the head H.

When the arm 14 is in contact with the low point of the cam edge of a disk 5, the blade 11, through the action of the member or spring 15, is in fully closed position with respect to the stationary blade 8 but as the shaft 2 rotates, the selected disk 5 will throw or swing the blade into open position. It is believed to be obvious that the extent of outward swinging movement of the blade 11 may be varied by proper endwise movement of the shaft 2 to bring the required disk 5 into working position with respect to the arm 14 of the blade 11.

The handle member M at diametrically opposed points is provided with the longitudinally disposed slots 16 which are positioned between the motor E and the head H. Passing out through these slots 16 are the outer extremities of the aligned straight arms 17. Each of these arms 17 exteriorly of the member H carries a slide 18 for a purpose to be later explained.

Interposed between the inner ends of the arms 17 and rigid therewith are the spaced annular members 19 which freely surround the shaft 2. The shaft 2 between these members 19 carries a surrounding outstanding flange 20, so that upon shifting the members 19 in either direction lengthwise of the shaft, one of the members 19 will contact the flange 20 and impose corresponding endwise movement to the shaft 2. The extent of this endwise movement of the shaft 2 determines which of the disks 5 will be brought into position for working the arm 14. These shifting movements are readily and conveniently effected from the action of a digit of the hand grasping the member M on either of the slides 18.

Side faces of the slides 18 are provided with index markings 21 for coaction with the indication graduations 22 positioned on the outer surface of the member M at required spaced points along the slots 16 and immediately adjacent thereto whereby the operator can readily determine the desired endwise adjustment of the shaft 2 to bring the desired disk 5 in working position with respect to the arm 14.

Leading from the motor E are the conductor wires 23 in required connection with the switch 24 mounted within the member M closely adjacent to the head or plate 1, the operating lever 25 extending out through a suitable opening 26 in the head or plate 1. Leading from the switch 24, and passing out through the head or plate 1, are the conductors 23 adapted for connection with a suitable source of electrical energy.

From the foregoing description it is thought to be obvious that a power operated scissors constructed in accordance with my invention is particularly well adapted for use by reason of the convenience and facility with which it may be assembled and operated.

What is claimed is:

1. Power operated scissors comprising a handle member, a stationary scissor blade carried by the member, a swinging blade pivoted to the stationary blade, an arm extending from the swinging blade, a motor carried by the handle member, an endwise movable shaft driven by the motor, a plurality of cams carried by the shaft, each of said cams having a high point differing from the remaining cams, and means for moving the shaft endwise to bring a selected cam into

working position with respect to the arm to move the swinging blade relative to the stationary blade.

2. Power operated scissors comprising a handle member, a stationary scissor blade carried by the member, a swinging blade pivoted to the stationary blade, an arm extending from the swinging blade, a motor carried by the handle member, an endwise movable shaft driven by the motor, 10 a plurality of cams carried by the shaft, each of said cams having a high point differing from the remaining cams, means for moving the shaft endwise to bring a selected cam into working position with respect to the arm to move the swinging blade away from the stationary blade, and pressure means for moving the swinging blade toward the stationary blade.

3. Power operated scissors comprising a handle member including a hollow head, a stationary scissor blade carried by the head and extending forwardly therefrom, a swinging blade coacting with the stationary blade, means for pivotally mounting the swinging blade, an arm extending from the swinging blade into the head, a motor 20 carried by the handle member, an endwise movable shaft driven by the motor, a plurality of cams carried by the shaft for selective contact with the arm for moving the swinging blade, each of said cams having a high point differing from 30 the remaining cams, and means for endwise moving the shaft to bring a selected cam into working position with respect to the arm of the swinging blade.

4. Power operated scissors comprising a handle member including a hollow head, a stationary scissor blade carried by the head and extending forwardly therefrom, a swinging blade coacting with the stationary blade, means for pivotally mounting the swinging blade, an arm extending 40 from the swinging blade into the head, a motor carried by the handle member, an endwise movable shaft driven by the motor, a plurality of cams carried by the shaft for selective contact with the arm for moving the swinging blade, each 45 of said cams having a high point differing from the remaining cams, a wall of the head having a slot, an arm extending into the head through the slot, and an operative connection between said second arm and the shaft to move the shaft endwise upon movement of the shaft along the slot to bring a selected cam into working position with respect to the arm of the swinging blade.

5. Power operated scissors comprising a handle member including a hollow head, a stationary scissor blade carried by the head and extending forwardly therefrom, a swinging blade coacting with the stationary blade, means for pivotally mounting the swinging blade, an arm extending 55 from the swinging blade into the head, a motor carried by the handle member, an endwise movable shaft driven by the motor, a plurality of cams carried by the shaft for selective contact with the arm for moving the swinging blade, each 60 of said cams having a high point differing from the remaining cams, the wall of the head at substantially diametrically opposed points being provided with slots, arms within the head and extending out through said slots, members interposed between and rigid with the arms, said members surrounding the shaft and being spaced apart lengthwise of the shaft, and an outstanding part carried by the shaft extending between the surrounding parts and with which said surrounding members contact to move the shaft

endwise upon shifting of the last named arms along the slots.

6. Power operated scissors comprising a hollow handle, a hollow head carried thereby, a stationary scissor blade carried by the head, a swinging blade pivoted to the stationary blade, an arm extending from the swinging blade into the head, a motor within the hollow handle, an endwise movable shaft driven by the motor and having a portion extending within the head, a plurality of cams carried by the portion of the shaft within

the head at points spaced along the shaft, each cam having a high point differing from the remaining cams, means operable exteriorly of the head for endwise moving the shaft to bring a selected cam into working position with respect to the arm of the swinging blade to move said swinging blade away from the stationary blade, and means for imposing pressure on the arm to move the swinging blade toward the stationary blade.

VINCENZO GAUDIO.
